UNITED STATES PATENT OFFICE.

EDWARD B. WESTON, OF DAYTON, OHIO, ASSIGNOR TO THE WESTON PAPER AND MFG. CO., OF DAYTON, OHIO, A CORPORATION OF OHIO.

DISPLAY RACK.

Application filed November 4, 1924. Serial No. 747,747.

This invention is an improvement in display racks, and more particularly in racks of the knock down type.

Display racks as usually constructed are permanent structures, occupying space wholly disproportionate to their weight. For this reason transportation charges are heavy, and the room required for their storage might be better utilized for some other purpose.

When constructed to be assembled on the spot where they are to be retailed or used, the construction is such that a skilled workman is required to assemble the parts, and when so assembled the rack is a permanent structure not capable of being again taken to pieces.

Furthermore the usual type of rack is not adapted for adjustment to suit the demands of the matter to be displayed as regards quantity, and dimensions. That is the supporting shelves or trays bear a fixed relation, so that the aggregate capacity of the rack cannot be varied, nor can the spacing of the shelves be changed to conform with the height of the articles to be displayed.

An object of the present invention is the provision of a rack of the character specified, composed of a minimum of parts easily assembled and disassembled.

Another object is the provision of a rack wherein after assembling, the parts may be connected into a rigid self-supporting rack structure, by certain easy and minor adjustments.

Another object is to provide a structure wherein the relative arrangement of the supporting trays or shelves may be varied, thus to vary the aggregate capacity of the rack.

Another object is to provide a construction of rack wherein a set of standards may be assembled with any selected one of a plurality of sets of trays thus to provide for the quick assemblage from stock parts of racks of any desired dimensions.

Another object is to provide a new and improved construction of tray or flanged shelf, formed from a single blank.

With these and other objects in view, the invention consists in the construction and novel combination of parts fully described hereinafter, illustrated in the accompanying drawings, and pointed out in the claim appended hereto, it being understood that various changes in the form, proportion,

size and minor details of construction, within the scope of the claim, may be resorted to without departing from the spirit of the invention.

In the drawings:

Fig. 1 is a perspective view of the improved rack.

Figs. 2 and 3 are sections on the lines 2-2 and 3-3 of Figure 1.

Fig. 4 is a plan view of a corner of a blank from which a tray or shelf is formed.

Fig. 5 is a perspective view of the stop for the nut of the corner connecting screw-bolts.

In the present embodiment of the invention, the improved rack is composed of a set of similar standards, usually four in number, and a set of trays, depending in number upon the capacity desired for the rack, and upon the dimensions of the articles to be displayed.

The standards 1 are of angle material, each comprising wings extending at a right angle, and each standard is provided at the junction of the wings, that is that the angle of the standard, with a plurality of keyhole slots 2. These slots are similarly arranged, each with its large end upward, and the arrangement and the size of the slots is the same for the standards of a set.

Each of the trays is composed of a base or bottom 3, and pairs of opposite side walls 4 and 5, the members of the pairs being similar, and differing slightly from the members of the other pair. The side walls 4 and 5 are at substantially a right angle to the base or bottom, or have portions thereof which occupy such position, and since the adjacent walls meet at a right angle, it will be obvious that the corners of the trays will fit closely into the angles or concave faces of the standards, with the wings of each standard lapping upon adjacent ends of adjacent side walls.

Each tray has in connection with each corner thereof a headed member for engaging the keyhole slots of a standard. In the present instance the headed members are screw-bolts 6. The bolts are passed inwardly through openings in the corners of the tray, with the kerfed heads 7 of the bolts outward and in position to be passed through the large ends of the keyhole slots.

Each bolt is engaged by a nut 8 inside the tray, and a stop plate or washer 9 is ar-

ranged on the bolt between the nut and the tray. Opposite side edges 10 of each washer are bent at such an angle to the body that when the body lies obliquely across the 5 corner of the tray the bent side edges 10 will lie smoothly against the inner faces of adjacent tray side walls.

In assembling the tray, the nuts 8 are loosened far enough so that the heads of the 10 bolts 6 may be passed through the keyhole slots of the set of standards at the height desired. When the heads of the bolts pass through the large portions of the slots, a slight downward movement of the tray with 15 respect to the standards will cause the shanks of the bolts to pass into the narrow portions of the slots, thus locking the standards and the trays together. The spacing of the key-hole slots in the standards corresponds to the 20 minimum spacing desired for the trays, and if a maximum capacity rack is desired, a tray is arranged at each set of keyhole slots. If a less capacity is desired or merely a greater spacing of the trays, the trays may 25 be omitted at the alternate sets of keyhole slots.

After the trays are assembled, by means of a screw-driver or the like, the bolts may be turned to tighten the nuts 8. This procedure draws the standards tightly against 30 the tray corners, and makes the rack a rigid structure, with however some elasticity and resiliency, because of the washers 9. These washers because of their arrangement, permit 35 a certain degree of movement with respect to the tray, to prevent injury to the bolt or to other parts. A rack is easily knocked down for storage or transportation, and when knocked down the standards nest 40 one into the other. A number of completed racks might be connected in one package, by superposing the trays and arranging the nested standards at the corners of the superposed trays.

45 Preferably the trays are constructed in the manner shown in Figures 3 and 4. Each tray is formed from a rectangular blank of suitable sheet material notched at its corners to provide the bottom or base 3 of suitable 50 dimensions, and pairs of opposite flaps, which when bent to shape form the side walls 4 and 5. The flaps 5 have extensions 55 at their ends, which are designed to be bent inwardly at right angles to the flaps, to abut the inner faces of the adjacent flaps

4 when the flaps are folded at right angles to the bottom. Referring to Figure 4 it will be noticed that the extensions 11 are notched at 12 between the flaps 4 and adjacent ends of the extensions. 60

The notches at the corners of the blank are cut to a greater depth than that actually required for the wall, and the outer corners of the flaps are beveled as shown at 13, over a depth corresponding to that of the material in the flap in excess of that required for the wall. This excess material indicated at 14 is bent over upon the inner face of the adjacent side wall, to provide a finish for the free edge of the wall and a 70 reinforce. In forming the blank into the tray, the portions 14 are bent over upon the flaps 4 and 5, the extensions 11 are bent at right angles to the flaps 5, and the flaps 5 are bent at right angles to the bottom 3. 75 Afterwards the flaps 4 are bent to shape. The blanks may be cut and shaped in any suitable manner.

In practice the top tray may be flush with the standard tops as shown, or the standards 80 may extend above the top tray, in which case they might be provided with ornamental tops. They may also be mounted on casters, and the bottoms thereof may have suitable feet or bases. 85

I claim:

A knock-down display rack including a set of standards and a plurality of removable trays, the standards angular in cross section and adapted to fit about the corners of the 90 trays, each standard having vertically aligned longitudinally extending slots in its angular portion, and each tray having at each corner a removable headed member for engaging the slots of the standards, the slots restricted 95 at their lower ends to prevent disengagement of the headed members, each of said members threaded at its inner end, a yieldable washer-plate in the corners of each tray through which its companion headed member extends, each washer-plate having bent ends 100 lying against the inner faces of adjacent tray side walls, and a nut engaging each member and bearing against its associated washer plate to yieldably clamp the 105 standards to the trays.

Signed at Dayton, in the county of Montgomery and State of Ohio this 31st day of October A. D. 1924.

EDWARD B. WESTON.
